UNITED STATES PATENT OFFICE

ERIC H. BRADLEY, OF DAYTON, OHIO, ASSIGNOR TO NATIONAL PUMPS CORPORATION,
OF DAYTON, OHIO, A CORPORATION OF OHIO

LIQUID DISPENSING APPARATUS

Application filed April 20, 1931. Serial No. 531,461.

This invention relates to liquid dispensing apparatus and more particularly to that type of apparatus commonly employed for dispensing gasoline, and is a continuation in part of the joint application of Hanna and Bradley, filed September 5, 1930, Serial No. 479,870.

One object of the invention is to provide such an apparatus with a hose support adapted to have interlocking connection with the hose nozzle of such a character that the nozzle can be quickly placed on and removed from the support and will be firmly supported thereby.

15 A further object of the invention is to provide such a hose support with means for preventing the opening of the nozzle valve while the nozzle is mounted on the support.

A further object of the invention is to 20 provide such a support with improved means for controlling the discharge of liquid from the apparatus.

Other objects of the invention will appear as the apparatus is described in detail.

25 In the accompanying drawing Fig. 1 is a side elevation of a portion of a liquid dispensing apparatus showing my invention applied thereto; Fig. 2 is a rear elevation of the switch and valve controlling mechanism; 30 and Fig. 3 is a section taken through the support on the line 3-3 of Fig. 1.

In the drawing I have illustrated one embodiment of my invention and have shown the same as applied to a dispensing apparatus 35 of that type commonly known as a meter pump. This apparatus comprises a discharge pipe 5 adapted to communicate with an underground tank and having interposed therein a rotary pump 6 which is operated by an

40 electric motor 7, the motor being controlled by a switch 8. A meter 9 is interposed in the discharge pipe beyond the pump, and connected with the outer end of the discharge pipe is a flexible hose 10, the pipe and the 45 hose constituting the discharge conduit for the apparatus. Interposed in the discharge pipe, between the meter and the flexible hose, is a cut-off valve 11.

The hose 10 has at its discharge end a 50 nozzle 12 provided with a valve 13. Pivottally

mounted on the nozzle is a lever 14 for actuating the valve and this lever is protected by a guard 15 rigidly secured to the nozzle and extending about the lever. The guard is provided with a slot 16 and the valve actuating lever has a slot 17 arranged in line with the slot in the guard. Mounted on a fixed part of the apparatus, in the present instance on the discharge pipe, is a hose supporting arm 18, here shown as a flat bar which projects laterally beyond the apparatus and is adapted to be inserted through the slots in the nozzle guard and lever to support the nozzle and hose when the latter are not in use. The arrangement is such that the nozzle may be quickly and easily placed upon the supporting arm or removed therefrom and when mounted thereon will be firmly supported and held against turning movement. The guard arm is of such a length that when the nozzle is supported thereon the outer end of the arm will lie close to the body of the nozzle and the outer portion of the arm has therein an opening 19 so arranged that it will be located on the outer side of the valve actuating lever when the nozzle is properly positioned on the supporting arm. This opening is adapted to receive a locking device, such as a padlock 20, which serves both to retain the nozzle upon the supporting arm and to prevent the operation of the valve actuating lever while the nozzle is supported on the arm.

The supporting arm may also have near its outer end a recess 25 to receive a part carried by the nozzle, such as the hook 26, and thus provide means for quickly engaging the nozzle with the supporting arm between delivery operations and when it is not desired to lock the apparatus.

If desired, the supporting arm may be provided with means for controlling the switch 8 and the cut-off valve 11 and, as here shown, a crank arm 21 is rigidly connected with the supporting arm for movement therewith and is connected by means of a link 22 with the switch 8 and by means of a link 23 with the cut-off valve 11. The arrangement is such that when the supporting arm is in a position to support the nozzle the switch will be open and the valve 11 closed. If desired, a

spring may be provided to raise the arm and thus close the switch and open the valve when the nozzle is removed from the arm. In the present arrangement the spring is applied to the link 22, as shown at 24. The weight of the nozzle and hose on the supporting arm will retain the switch open and valve closed so long as the nozzle is supported on the arm. When the nozzle is removed for use the supporting arm is moved upwardly into the position shown in dotted lines, either manually or by the spring, thus causing the crank arm 21 to close the switch and to open the valve 11.

15 While I have shown and described one embodiment of my invention I wish it to be understood that I do not desire to be limited to the details thereof as various modifications may occur to a person skilled in the art.

20 Having now fully described my invention, what I claim as new and desire to secure by Letters Patent, is:

25 1. In a liquid dispensing apparatus, a discharge conduit including a flexible hose, a nozzle on the delivery end of said hose having a valve, a lever for operating the valve, a guard for said lever secured to the nozzle, said lever and said guard having alined openings, and a support for said nozzle adapted to extend through the openings in said guard and said lever and to have supporting engagement therewith.

30 2. In a liquid dispensing apparatus, a discharge conduit including a flexible hose, a nozzle on the delivery end of said hose having a valve, a lever for operating the valve, a guard for said lever secured to the nozzle, said lever and said guard having alined openings, and a supporting arm adapted to extend through the openings in said guard and said lever and having an opening to receive a locking member to hold said lever against movement while said nozzle is supported on said arm.

35 3. In a liquid dispensing apparatus, a discharge conduit including a flexible hose, a nozzle on the delivery end of said hose having a valve, a lever for operating the valve, a guard for said lever secured to the nozzle, said lever and said guard having alined openings, and a support for said nozzle adapted to extend through the openings in said guard and said lever and to have supporting engagement therewith, said support having a recessed portion with which a part carried by said nozzle may be engaged to support said nozzle thereon independently of the opening in said guard.

40 4. In a liquid dispensing apparatus, delivery mechanism including a controlling device, a housing enclosing said delivery mechanism and having a slot therein, a discharge conduit leading from said delivery mechanism to the exterior of said housing and including a flexible hose, a nozzle on the delivery

45 end of said hose having a valve, a lever for operating said valve, a guard for said lever secured to said nozzle, said lever and said guard having alined openings, a supporting member pivotally mounted within 70 said housing, extending through said slot and adapted to enter said alined openings in said lever and said guard, and means for operatively connecting said supporting member with said controlling device, said housing 75 having an opening above said slot to receive the end of said nozzle when the latter is placed on said supporting member, said opening being arranged to prevent the vertical movement of said nozzle while said lever and said guard are in supporting engagement with said supporting member.

50 In testimony whereof, I affix my signature hereto.
